UNITED STATES PATENT OFFICE.

WILLIAM S. WHITE, OF TRACY CITY, TENNESSEE.

CULTIVATOR.

1,213,050.

Specification of Letters Patent. Patented Jan. 16, 1917.

Application filed May 2, 1916. Serial No. 94,957.

To all whom it may concern:

Be it known that I, WILLIAM S. WHITE, a citizen of the United States, residing at Tracy City, in the county of Grundy and State of Tennessee, have invented new and useful Improvements in Cultivators, of which the following is a specification.

This invention relates to cultivators, and it has particular reference to a disk cultivator of the sulky type.

The invention has for its object to produce a simple and efficient implement of this class which may be readily drawn by a single draft animal.

15 A further object of the invention is to produce a simple and efficient disk cultivator wherein the disks may be readily interchanged from right to left so as to move the dirt toward or from the plants, as may be required.

20 A further object of the invention is to simplify and improve the general construction, arrangement and combination of parts entering into the construction of the device.

25 With these and other ends in view which will readily appear as the nature of the invention is better understood, the same consists in the improved construction and novel arrangement and combination of parts which 30 will be hereinafter fully described and particularly pointed out in the claims.

In the accompanying drawings has been illustrated a simple and preferred form of the invention, it being, however, understood 35 that no limitation is necessarily made to the precise structural details therein exhibited, but that changes, alterations and modifications within the scope of the claims may be resorted to when desired.

40 In the drawings, Figure 1 is a top plan view of a cultivator constructed in accordance with the invention, the seat and seat support having been broken away. Fig. 2 is a view partly in side elevation and partly in 45 longitudinal section taken on the line 2—2 in Fig. 1. Fig. 3 is a vertical transverse sectional view taken on the line 3—3 in Fig. 1. Fig. 4 is a longitudinal sectional view of one of the axles. Fig. 5 is a sectional view 50 of one of the journal boxes. Fig. 6 is a perspective detail view of one of the bearing sleeves. Fig. 7 is a side elevation of one of the disks. Fig. 8 is a side view of one of the washers. Fig. 9 is a side view of a spading 55 disk sometimes used in connection with the device.

Corresponding parts in the several figures are denoted by like characters of reference.

The frame of the machine includes a pair of thills or shafts 15 which are connected together and spaced apart by means of cross bars 16, 17 and 18 which have been shown as consisting of metallic angle bars. The intermediate cross bar 17 and the rear cross bar 18 support arches 19, 20 which are connected together by longitudinally disposed braces 21 supporting the driver's seat 22. A draft element, such as a swingletree 23, is mounted on the front cross bar 16.

Tool carrying standards S, S', four in 70 number, are carried by the front and intermediate cross bars 16, 17, each of said standards being composed of a substantially triangular frame, one side of which, 24, is bolted or otherwise secured on the end faces 75 of the cross bars 16, 17; another side member 25 which is integral with the side member 24 is bent downwardly and rearwardly with respect to the side member 24; the third side member 26 constitutes a brace 80 which is terminally connected with the side members 24 and 25 at the upper forward end of the former and adjacent to the lower rearward end of the latter, the parts being connected together by bolts, rivets or other 85 well known fastening means. The side member 25 is extended downwardly to form a shank 25', and the lower extremity of the side member 26 forms a shoulder or abutment 26' adjacent to said shank. The standards S, which are disposed closely together under the middle portion of the frame, are 90 connected together by a cross piece 27 to prevent wabbling and vibration when the machine is in operation.

95 Each of the standards supports a journal box B consisting of a block or casting having a transverse bore 28 and an aperture or socket 29, said socket being adapted to receive the shank 25' at the lower extremity of the member 25 of the standard on which it is mounted and on which it is secured by means of a cotter pin 30. The block B is provided with threaded apertures 31, 32 communicating with the bore 28, one of said 100 apertures being for the reception of a set screw 33 while the other receives an oil cup 34 having a threaded shank or stem 35 which also extends through an aperture 36 in a bearing sleeve 37 with which the box is 105 provided.

110 For the equipment of the improved cul-

tivator four of the bearing boxes B are required, one of said boxes being mounted on each of the standards S and S' where they are secured by the cotter pins 30. Each 5 pair of boxes afford bearings for an axle 38 the body or main portion of which is of non-circular cross section, preferably square, while the ends of said axle are reduced to form spindles 39 that are journaled in the 10 sleeves 37. Each axle is provided with a spacing sleeve 40 adjacent to the ends of which are mounted washers 41 and disks 42, the latter being secured by additional washers 43 and keys 44, said keys being 15 driven through transverse slots 45. Additional washers 46 are interposed between the keys 44 and the ends of the sleeves 37, permitting the axles carrying the disks to turn freely. The several washers 41, 43 and 20 46 are of similar construction, as will be seen in Fig. 8, where one of the washers 41 has been shown. Each washer is provided with an eye or aperture 47 of non-circular shape, preferably square, to fit non-rotatably on the non-circular portion of the axle.

It will be seen that the limbs or side members 25 of the standards S project to the rearward of the corresponding limbs or side members of the standards S'; the result is 30 that the axles 38, when mounted in position, will be angularly disposed, as best seen in Fig. 1. In said figure the disks at the two sides of the machine are disposed with their concave faces outward; it will be seen that 35 by loosening the cotter pins 30, the box carrying the shafts and the disks may be detached, permitting the shafts and related parts to be interchanged between the two sides of the machine, thus disposing the 40 disks with their convex faces outward.

In Fig. 9 there has been shown a spading disk 48 having equidistant notches or recesses 49 around the circumference thereof, producing a construction whereby the well 45 known or spading action will be obtained.

Connected with the rearward cross bar 18 of the frame are arms or brackets 50 carrying disk engaging scrapers 51 whereby the disks will be free from adhering dirt. These 50 scrapers are particularly useful when sticky or clayey soil is encountered. When light sandy or loamy soil is operated upon the scrapers may be dispensed with.

From the foregoing description taken in

connection with the drawings hereto annexed, it will be seen that I have produced a simple and efficient cultivator which may be readily drawn by one horse and which will be found particularly useful for truck farming and the like, especially where the 55 ground is more or less filled with roots and stubble which would tend to hinder the progress of an ordinary cultivator. The disks of the improved machine will roll unobstructedly in such ground and will cut 60 and sever the obstructions below the surface without bringing the same to the surface, thus producing a condition where roots and the like will quickly become decomposed and add fertility to the soil. 65

Having thus described the invention, what is claimed as new, is:—

1. In a cultivator, a frame having standards, boxes carried by the standards, bearing sleeves in the boxes, an axle of non-circular cross section having rounded spindles 70 engaging the boxes, a spacing sleeve on the non-circular portion of the axle, disks mounted on the non-circular portion of the axle, washers interposed between the disks 75 and the ends of the spacing sleeve, washers mounted on the non-circular portion of the axle adjacent to the outer faces of the disks, keys driven transversely through the axle 80 and engaging the last mentioned washers to 85 clamp the disks between said last mentioned washers and the first mentioned washers, and additional washers mounted on the non-circular portion of the axle between the 90 keys and the bearing sleeves. 95

2. In a cultivator, a frame, standards carried by the frame, each standard consisting of a triangular frame composed of a member bent to form two sides of the frame and a second member secured on the first member to form the third side of the frame and constituting a brace, a portion of the first member being extended below the second member to form a shank and the lower extremity of the second member constituting 100 a shoulder, in combination with a bearing box having a socket engaging the shank, the latter being provided with a key to retain the box in position. 105

In testimony whereof I affix my signature.

WILLIAM S. WHITE.
